UNITED STATES PATENT OFFICE

WILLIAM F. VAN VACTOR, OF PORTLAND, OREGON

EXPLOSIVE POWDER

No Drawing.

Application filed August 30, 1928. Serial No. 303,127.

The invention relates to the manufacture of explosive powders of the high explosive type that do not detonate when fired and has for its principal object the provision of a powder that can be manufactured with reasonable safety and one in which the granulation of the product after mixing and drying is readily and effectively secured.

The ingredients employed in making my improved explosive comprises potassium chlorate, granulated sugar, Irish moss jelly, water, and crude fuel oil. The Irish moss jelly is prepared by covering the dry moss with warm water and allowing it to steep for twelve hours, and the percentage of the Irish moss jelly in the mixture is always one-half of one per cent by weight. The percentage of the crude fuel oil in the mixture is one-half of one per cent. The percentage of water in the mixture is two per cent. The remaining 97% of the composition is made up of potassium chlorate and granulated sugar, and the potassium chlorate may be varied from forty to sixty per cent depending on the nature of the powder that is desired, and the remainder of the composition is sugar. By varying the proportions of the potassium chlorate and sugar, which is preferably of the granulated type, explosive powders of varying strengths in accordance with the purpose for which the powder is to be used are produced, it being understood that the higher the percentage of the potassium chlorate the higher the explosive force of the powder, the mixtures having the lower percentages of potassium chlorate being of the progressive burning and propelling type of explosives.

In making the explosive the water is added to the sugar and boiled without stirring to a temperature of 240 degrees Fahrenheit, or to such a time that the boiled sugar becomes brittle and cracks when dropped into cold water. The Irish moss jelly is then stirred into the boiling sugar and the product removed from the fire. The potassium chlorate is then stirred into the mixture and thoroughly agitated while adding the fuel oil which must be added before the mixture is too dry to stir. The product is then

spread out and allowed to dry for at least twenty-four hours and after it has thoroughly dried is ready to pack for use.

The Irish moss jelly is included in the mixture because after the product has dried it causes a ready granulation of the dried product and also provides a binder for the ingredients.

I have also found that by varying the degrees of heat used in boiling the sugar between 235 degrees and 275 degrees Fahrenheit, the texture of the finished product is varied, the higher heated products being capable of more finely division in granulation.

The powder is particularly adapted for use in blasting either rock or stumps and for mining, being capable of use in underground work without causing ill effects from fumes, such for instance as headaches.

Should it be desired to eliminate danger of ignition from friction crude fuel oil may be mixed with the powder in the proportions of one part of the oil to fifty parts of the powder. This will make the powder semi-plastic and will further make the explosive moisture resistant.

What is claimed is:—

1. In an explosive mixture, including a chlorate and sugar, and a binder and granulating element consisting of Irish moss jelly.
2. An explosive mixture, consisting of a chlorate, sugar, fuel oil, Irish moss jelly and water.
3. An explosive mixture, consisting of chlorate of potash from forty to sixty per cent by weight, sufficient sugar to make with said chlorate a total of ninety-seven per cent, Irish moss jelly one-half of one per cent, fuel oil one-half of one per cent, and water two per cent.

In testimony whereof I affix my signature.
WILLIAM F. VAN VACTOR.
